UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

RADIO SIGNALING SYSTEM.

Application filed May 10, 1915. Serial No. 27,025.

To all whom it may concern:

Be it known that I, LEE DE FOREST, a citizen of the United States, residing in New York, county of Bronx, State of New York, 5 have made a certain new and useful invention in Radio Signaling Systems, of which the following is a specification.

This invention relates to radio signaling systems.

10 The object of the invention is to provide a simple and efficient system for use in radio signaling.

15 A further object of the invention is to provide a signaling system of the class referred to wherein the amplitude of the radiated wave trains is effectively controlled by a signaling device.

Further objects of the invention will appear more fully hereinafter.

20 The invention consists substantially in the combination and location of parts, and the various circuit arrangements associated therewith, all as will be more fully herein-after set forth, as shown in the accompanying drawing, and finally pointed out in the 25 appended claims.

Referring to the drawing,—

Fig. 1 is a diagrammatic view showing one form of circuit arrangement embodying 30 my invention.

Fig. 2 is a similar view showing a modified arrangement for accomplishing the purposes of my invention.

The same part is designated by the same 35 reference numeral wherever it occurs throughout the several views.

In accordance with my invention I provide a source of electrical energy indicated at 1. In the form shown, but to which I am 40 not to be limited or restricted, 1 is a direct current generator, regulated by the adjustable resistance 2. Connected in the circuit of the current source, is a capacity, such as a condenser 5, and an inductance 6 in series therewith, and choke coils 3, 3. A spark gap, illustrated at 4 is connected across the inductance 6 and capacity 5 forming therewith an oscillating circuit which may be utilized as a source of continuous oscillations. A radiating antenna 8 is connected 45 to earth or ground 9 through inductance 7 which may be the secondary coil of an oscillation transformer the primary coil of which is the inductance 6 hereinbefore identified. 50 Any other suitable form of coupling may

employed. An audion 10 including therein the well known forms of hot and cold electrodes such as the cold plate or wing electrode 11, the grid or intermediate cold electrode 12, and the hot filament electrode 13, 60 is associated with the antenna earth system through the spur 20 connecting the cold electrode 11 to the antenna system. The filament electrode 13 is heated by a current source such as a battery 16, and controlled 65 by the variable resistance 17 in the usual and well known manner. A microphone or other suitable signaling device, as illustrated at 14, is connected between the grid electrode 12 and the filament electrode 13. If 70 desired, and as shown, an auxiliary source of current such as a battery 15 may be included in this circuit, preferably with its negative terminal connected to the grid electrode so as to normally maintain a negative 75 charge upon said electrode, but it is obvious that my invention is not to be limited in this respect.

Fig. 2 is similar to Fig. 1 except that in this arrangement the microphone or signaling device is associated with the grid electrode by means of an additional circuit containing battery 21 and primary winding 19 of a transformer, the secondary 18 of which is connected to the grid and filament electrodes 12, and 13, respectively. It is obvious that any other form of coupling may be employed to couple the circuit of the microphone to the circuit of grid electrode 12. 80 85

In this arrangement an additional current source, such as a battery 22 is connected to the wing or plate circuit of the audion, to normally charge the wing or plate 11 positively relative to the filament electrode 13. 90 95 In both forms of my invention shown in the drawing, the plate or wing electrode 11 is in electrical connection to one side of the filament electrode 13, and in the arrangement shown in Fig. 2, the current source 100 22 is located in this circuit connection which includes the spur connection to the antenna.

By means of the circuits here shown a shunt path from the antenna to the earth is provided through the gas of the audion and completely around the inductance 7 of the antenna earth system. The conductivity of this gas path is more or less affected by the electric charge momentarily residing in the grid electrode 12. The intensity of this 105 110

charge is in turn affected by the signaling device, such as the microphone 14 which controls the potential impressed on the grid electrode 12 by the current source 15, either 5 directly as indicated in Fig. 1, or inductively, or otherwise, as indicated in Fig. 2. In this way, a signal, such, for illustration, as a voice spoken into a microphone 14, will control the degree of shunting resistance 10 offered in the earth shunt circuit of the antenna system and thereby control the amplitudes of the radiated wave trains in accordance with the voice currents through the microphone.

15 The arrangements shown and described are somewhat similar, and perform similar functions to those shown in Figs. 12 and 14 of my Letters Patent No. 943,969, granted to me December 21, 1909, but my present 20 invention illustrates a marked improvement thereover in the method of controlling radiation amplitudes by means of a signal, such as a voice.

25 While I have set forth the objects and nature of my invention and various arrangements for the accomplishment thereof, it will be understood that many other arrangements will occur to those skilled in the art, without departing from the broad scope of 30 my invention as defined in the claims, and therefore, what I claim as new and useful

and of my own invention and desire to secure by Letters Patent, is,—

1. In a radio signaling system, a source of high frequency oscillating current, a radiating antenna system associated therewith, an evacuated vessel containing hot and cold electrodes, a spur to the antenna connected to a cold electrode of said evacuated vessel, and an earth connection to the hot electrode 35 of said vessel, means for impressing a positive charge of current upon said cold electrode and means for varying the conductivity of the space in said evacuated vessel between said hot and cold electrodes. 40

2. A system comprising an arc generator, a signal conductor in which said generator produces high frequency waves, a current supply line for said generator, a unidirectionally conducting electron discharge device operatively connected to and energized by current transferred through said line, and signal controlled means for varying the impedance of said discharge device. 45

3. A system comprising an arc, a unidirectionally conducting electron discharge device having a space current path, and a common source of current supply for said arc and said path. 55

In testimony whereof I have hereunto set 60 my hand on this 7th day of May A. D., 1915.

LEE DE FOREST.
